United States Patent Office

Des. 219,814
Patented Feb. 2, 1971

219,814

BLOW GUN

Paul E. Gaylord, 2504 NW. 22nd Court,
Miami, Fla. 33142

Filed Nov. 29, 1968, Ser. No. 14,725

Term of patent 14 years

Int. Cl. D22—02

U.S. Cl. D22—3

FIG. 6

FIG. 4

FIG. 5

FIG. 1 is a side elevational view of a blow gun showing my new design.

FIGS. 2 and 3 are top and bottom plan views respectively.

FIGS. 4 and 5 are front and rear elevational views respectively on a greatly enlarged scale.

FIG. 6 is a perspective view on an enlarged scale, the barrel being broken away for convenience of illustration.

I claim:

The ornamental design for a blow gun, substantially as shown and described.
